UNITED STATES PATENT OFFICE.

MARTA OATMAN, OF LOS ANGELES, CALIFORNIA.

DESIGN FOR A DOLL.

Application filed October 6, 1925. Serial No. 15,036. Term of patent 3½ years.

To all whom it may concern:

Be it known that I, MARTA OATMAN, a citizen of the United States, and a resident of the city of Los Angeles, in the county of Los Angeles and State of California, have invented a new, original, and ornamental Design for a Doll, of which the following is a specification, reference being had to the accompanying drawings, forming part thereof.

the front being shown in this instance as white;

Fig. 2 is a reverse view thereof; the fabric forming the reverse being shown in this instance as black; and having a face, whereby a double-faced doll is obtained.

I claim:

The ornamental design for a doll, substantially as shown and described.

In testimony whereof I have hereunto set my hand.

MARTA OATMAN.
